UNITED STATES PATENT OFFICE.

JOHN C. DALLAM, OF SCHENECTADY, NEW YORK, ASSIGNOR TO STANLEY ELECTRIC MANUFACTURING COMPANY, OF PITTSFIELD, MASSACHUSETTS, A CORPORATION OF NEW JERSEY.

ATTACHMENT-PLUG.

964,619.

Specification of Letters Patent. Patented July 19, 1910.

Application filed January 11, 1905. Serial No. 240,547.

To all whom it may concern:

Be it known that I, JOHN C. DALLAM, a citizen of the United States, residing at Schenectady, county of Schenectady, State 5 of New York, have invented certain new and useful Improvements in Attachment-Plugs, of which the following is a specification.

The present invention relates to connectors for electric conductors, and more particularly to attachment plugs designed for use 10 in connecting the feed wires of small electrical apparatus such as fan motors, heaters, portable lamps, etc., to a service circuit by the mere insertion of the plug into the socket 15 or receptacle of the ordinary incandescent lamp.

The object of the invention is to provide a simple, compact and highly efficient device 20 of this character which may be readily separated so that the part carrying the contacts for engagement with the contacts of the socket or receptacle may be independently rotated into or out of operative position, and the other member to which the feed wires 25 are attached connected thereto without twisting or untwisting of the feed wires and, moreover, to afford an easily severable joint whereby the application of tensile strains to the feed wires will merely cause a separation 30 of the parts and protect the socket or receptacle and its support from injury.

In carrying out my invention I provide an insulating base section and a separable wire engaging section. The former section is 35 provided at one end with metallic contacts adapted to connect with the contacts of a socket or receptacle and electrically connected to metallic jaws or clips at the opposite end for detachably engaging projections on 40 the separable wire engaging section. The latter section has an insulating disk, upon one side of which are mounted the engaging projections, and upon the other side are mounted suitable binding posts and cut-out 45 devices, and surrounding the edge of the disk, the binding posts and cut-out devices, is a suitable protecting cap.

For a more complete understanding of the invention reference may be made to the following detailed description and the accompanying drawing forming a part of this specification in which,

Figure 1 is a vertical section of a separable attaching plug embodying one form 55 of my invention; Fig. 2 is a plan view of the

top end of the insulating base section; and Fig. 3 is a bottom plan view of the separable section.

The base section 1 is of porcelain or other suitable insulating material with its outer 60 surface in two cylinders 2 and 3, the lower portion 3 being of smaller diameter and provided with a threaded contact shell 4 similar to the side contact of an Edison lamp, while the lower end is frustoconical and receives on its end surface a washer 5 through 65 which a rod or screw 6 extends upwardly axially of the base.

The upper portion of the base section 1 is provided with two recesses 7 and 8. The 70 larger recess 7 extending from near the periphery to the opposite side of the axis receives an angular clip or jaw 9 having its transversely-disposed arm 10 apertured and threaded for engagement with the upper 75 end of the axial screw 6, while the longitudinal arm 11 is provided with a reverse curve to afford a grip for a corresponding part on the separable section. The smaller recess 8 is separated from the larger recess 80 7 by a septum 12, and at the bottom thereof is an aperture 13 through which extends a straight shanked spring clip or jaw 14 which is connected at its lower end to the lower 85 edge of the screw shell by solder or other suitable means. The upper end 15 of the clip or jaw 14 is provided with a reverse curve similar to that in clip or jaw 9, but oppositely disposed. The screw shell 4 and the clip or jaw 14 carried thereby are held 90 in position on the base by a screw 16 extending longitudinally through the upper base portion and engaging a suitable lug (not shown) on the upper edge of the screw shell.

The separable section 17 has an insulating 95 disk 18 of fiber or other tough insulating material with metallic projections or fingers 19 secured to the lower surface thereof for electrically connecting the sections and mechanically holding them in engagement. 100 The projections or fingers 19 are formed out of flexible sheet metal and have their lower ends 20 reversely curved corresponding to the upper curved ends of the jaws or clips 9 and 14, and at their upper ends they 105 are formed with segmental lugs 21 which are apertured and threaded for the reception of fastening and binding screws 22, 23 and 22', 23' extending through the disk 18. The disk 18 is provided near its periphery 110

with a fifth screw 24 which serves as a binding screw for one of the feed wires 25 and an end of a fuse 26. The opposite end of the fuse may be connected to either of the binding screws 23 or 23', while the second feed wire 25 is connected to the other.

The protecting cap 27 is of sheet metal made hemispherical in shape similar to the caps of the ordinary lamp sockets, and is connected to the insulating disk 18 by radial screws 28 extending through the lower sides of the cap 27 and engaging tapped holes in the disk. By securing the disk 18 slightly above the lower edge of the cap, as shown in Fig. 1, the latter is adapted to serve as a guard flange 29 for the joint between the two sections of the plug.

I do not desire to restrict myself to the particular form of construction of parts herein described and shown, since it is apparent that they may be changed and modified without departing from my invention.

What I claim as new and desire to secure by Letters Patent of the United States, is,—

1. A separable electric connector comprising a one-piece base of insulating material provided at one end with recesses, contact clips or jaws located in said recesses, and center and side contacts at the other end of the base electrically connected to said clips or jaws.

2. A separable electric connector comprising a one-piece base of insulating material provided at one end with recesses, contact clips or jaws located in said recesses, a shell contact surrounding the other end of said base and connected to one of said clips or jaws, and a center contact connected to the other clip or jaw.

3. A separable electric connector comprising a one-piece base of insulating material provided in the upper end with recesses, contact clips or jaws located in said recesses with their outer ends below the end surface of the base, a shell contact mounted upon and surrounding the lower end of said base and connected to one of said clips or jaws, and a center contact electrically connected to the other clip or jaw.

ing a one-piece base of insulating material provided in the upper end with recesses, contact clips or jaws located in said recesses with their outer ends below the end surface of the base, a shell contact mounted upon and surrounding the lower end of said base and connected to one of said clips or jaws, and a center contact electrically connected to the other clip or jaw. 45

4. A separable attaching plug comprising 50 an insulating base part having integral cylindrical end portions of different diameters, metal contacts mounted on the smaller end portion, recesses formed in the opposite end, an angular jaw of flat metal arranged in one 55 of said recesses and connected to one of the contacts by an axial screw or rod, a second jaw of flat metal arranged in the other recess and extended into engagement with the other contact, and a separable wire-carrying member 60 provided with fingers or projections adapted to engage said jaws.

5. In an electrical connector, the combination of a base of insulating material having two recesses in the upper end and a radial 65 recess in the lower end, center and side contacts mounted on the lower end of the base, contact clips in the recesses at the upper end, one of which is connected to the side contact, a conductor extending from the 70 center contact axially through the base, and a radial connector attached thereto and connected to the second contact clip.

In witness whereof, I have hereunto set my hand this 9th day of January, 1905.

JOHN C. DALLAM.
